UNITED STATES PATENT OFFICE.

CHARLES O. KARPF, OF NEW YORK, N. Y.

CONTINUOUS PROCESS OF ORNAMENTING FLOOR COVERINGS.

No Drawing.

Application filed March 21, 1927. Serial No. 177,214.

This invention relates to a process for ornamenting floor covering; more particularly for a process of continuously ornamenting floor covering of the felt base variety.

5 Where I have attempted to ornament floor covering, particularly at relatively low cost, as in making felt base products, the process of depositing the ornamental pattern upon the felt base by the mash block, utilizing as 10 the coating material viscous paint base products, I have found not only is the process not susceptible of continuous operation with sufficient speed due to the time attendant to proper drying and character of feed of the 15 web of material relatively to the impressing members, but, also, the nature of the ornamentation is confined to designs of a relatively simple character.

An object, therefore, of my invention resides in the provision of an improved process 20 for ornamenting floor covering, particularly of the felt base variety, including first the modification of the surface of a web of material, such as felt base, with a surface finish 25 comprising a sealing coat of the character which may have impressed thereon an ornamentation utilizing printer's ink as may be deposited on an engraved plate, having fineness of definition of ornamentation equivalent to that in printing upon paper whereby 30 also the speed of operation accompanying the printing on paper is obtained. Following the step of ornamenting, a wear coat, sufficiently transparent to make visible therethrough the 35 ornamentation, is deposited on the surface coating of printing ink, the composite layers having the wearing characteristics of the final coat, yet including definition, brilliancy and complexity of design heretofore not attainable by the mash block process and far 40 exceeding the mash block process in speed of operation and production.

In the practice of my invention, I first provide a printing plate preferably in the 45 nature such as may be mounted on a rotary printer's roll. The printing plate preferably includes a design adaptable for making repeats upon a continuous web to produce an ornamented web of continuous design or, 50 for certain purposes, the plate may be of the character which will deposit repeats, each forming a unitary design. The plate is preferably made by selecting a design which may be a natural product, such as wood or marble blocks. Photographically the design is

reproduced, the subject matter being preferably marble tile, grained wood or any ornate surface without regard to complexity of design. By well known processes, from the negative so obtained a positive is produced and then a sensitized photogravure carbon tissue paper is made, such as intaglio process of printing. An etched plate is thereafter produced of the character referred to in the printing art as the Benday process, 60 thus affording the reproduction of various shades of the same primary color with a single plate. It is preferred to make the plate utilizing screen of relatively coarse texture, for purposes which will hereinafter appear. 70 The production of a plate of this character breaks up the surface into minute cells and where the screen used is of a relatively coarse texture, the quantity of printing ink capable of being retained makes the same particularly 75 admirably suitable in the art of making floor covering, as will more clearly appear as this description proceeds.

For ornamenting floor covering, it is preferred to utilize a felt base webbed material 80 procurable on the market and comprising an asphaltic or similar bitumen impregnated felt having one face thereof already backed by a paint coat. This web is then fed through a roll to apply a sealing coat which may be 85 of any desirable tone and color, the color being chosen such as will intensify and blend with the primary design to be impressed thereover. This sealing coat is suitably doctored to produce a texture which will take 90 printing thereon from a printing plate as previously prepared. The web is thereafter fed through the printing plate, a feeding roll for ordinary printer's ink being used to deposit the necessary material upon the plate. 95 For certain purposes, the plate is doctored or wiped to remove excess printing ink therefrom before the impression is made on the felt base.

As has been previously indicated, the plate 100 having been made through a relatively coarse textured screen, the cells so produced will serve to hold a relatively large quantity of printing ink. Complete deposition of the printing ink upon the felt base is facilitated 105 by reason of the highly resilient character of the felt base surface. It will be apparent that by this process there may be deposited sufficient printing ink to give the necessary brilliancy and surface ornamentation upon the 110

felt base. However, as the printing plate surface is coarse textured and formed with minute cells, the design reproduced therefrom will have the same character and, for certain purposes, undesirably discloses this screen texture upon the felt base. For blending and obliterating the celled texture of the design on the felt base I immediately, while the printing ink is still wet, reflexively bend the web 10 of material over the first of a group of festooning rolls. It should be observed that the bend made is as sharp as will be permitted without danger of breaking the web. Due to the relative thickness of the felt base, the surface 15 having the printing thereon will be alternately compressed and expanded. This action serves to blend the printing ink deposited upon the surface to obliterate and blend the cell structure.

20 In progressively feeding the web of material through the series of rolls including, first, the sealing coat and then the printing coat, the time element is such as to permit the printing ink to thoroughly dry. I have found that a period of less than an hour is sufficient to dry the printing ink ornamented surface to permit the application thereto of an additional coat, which may be another ornamental coat, where it is contemplated to 25 produce a multi-color effect. However, for similar multi-shade, single color ornamentation, the ornamented surface has applied thereto a final coat. For this purpose the web is drawn through a varnishing or lacquering bath or series of rolls where a coat of resinous varnish may be applied. It is preferred, however, to have the final coat of a varnish of a gelatinized nitrocellulose base or similar gelatinized cellulose compound, such as acetyl 30 cellulose, cellulose ethers or the like. It will be observed that where I refer to varnish, I mean to include thereby varnishes of the resin base, artificial or natural, or cellulose compound base.

35 Normal time for drying, accompanied by baking or heating to facilitate the rapidity of this action, follows the application of the final coat. These coats may be in quantities in accordance with the thickness desired.

40 The product so prepared forms the final

55 floor covering. It will be observed that by the process described I have been enabled to continuously and rapidly provide a floor covering eliminating expensive machinery normally used for applying ornamental coats 60 characteristic of the mash block process. The time element for producing the felt base is materially shortened as the drying required for paint coat ornamented floor covering is entirely eliminated. It will be observed that 65 though approximately one hour has been set forth as sufficient to dry the printing ink surface, by the addition of suitable ink dryers this time also may be materially reduced.

70 It will further be observed that by reason of the nature of the engraved plate used, I may not only obtain intricate designs not possible by the mash block ornamenting process, but also by using the celled plate upon the relatively resilient floor covering base, I may deposit sufficient printing ink and coloring matter to give the necessary brilliancy to the 75 ornamented surface.

80 It will also be observed that even though I may use a printing plate of relatively coarse textured surface, tending to give a celled structure to the ornamented surface, by the novel step of obliterating the sharp outlines of the cell structure, I obtain a design blended throughout to give the appearance of that 85 which may be produced by as fine a printing plate as used on highly glazed printing paper.

Having thus described my invention and 90 illustrated its use, what I claim as new and desire to secure by Letters Patent, is—

95 The process of forming a floor covering which consists in applying to a waterproof flexible felt base of the flooring type a sealing coat of paint, which coat is smooth and flat, then applying to the sealing coat a decoration in ink from an etched plate having a wide mesh screen, then before the ink is dry reversely bending the flexible body so as to blend out the effects of the screen, and finally covering the body with a transparent wear coating.

100 In witness whereof I have signed and sealed this specification.

CHARLES O. KARPF.
